COVER FOR HINGES OR THE LIKE

Charles Colucci, New York, N. Y.

Application March 16, 1940, Serial No. 324,304

13 Claims. (Cl. 16—148)

This invention relates to covers for hinges, in particular for pin hinges having cam characteristics, wherein a moving leaf has a rise or fall while swinging.

The present application is a continuation-in-part of my copending application Serial #208,138 filed May 16, 1938, now Patent No. 2,205,396 granted June 25, 1940, wherein I have disclosed a form of the present invention as applied to a cam hinge.

It is a general object of my invention to provide a cover for hinges or the like that is simple in construction, easy to apply or remove, that permits free action of the hinge knuckles, that is well suited to protect a person's fingers from injury, when the hinge embodies cam parts and that will improve the appearance of the hinge it covers.

Further objects of the invention are to provide: a hinge cover embodying cover means for the hinge knuckles and resilient attaching means to retain the cover in place on the hinge; a simple cover for hinges comprising a shaped sheet material member embodying resilient end straps adapted to secure the cover to suitable projections at the ends of the hinge and permit relative movement of the cover in response to movement of the hinge leaf; a cover for hinges comprising a shaped body portion to cover the hinge knuckles and embodying attaching portions having resilient connection to the body portion; a cover for hinges capable of displacement with the moving leaf of the hinge and adapted to return to its original position together with the moving leaf; a cover for hinges comprising a substantially rigid body portion and resilient head portions at each end of the body portion; a cover for hinges comprising a substantially U-shaped body of flexible material the sides of which are sufficiently long to bear against the hinge leaves when said leaves are in closed position; a molded cover member for hinges embodying end portions of rubber or other plastic material of resilient characteristics; a cover for hinges having projecting pintle heads comprising a resilient body portion and resilient ends adapted to be snapped over the pintle head and have substantial frictional engagement with said heads; a hinge cover comprising a shaped cover portion and a pair of tabs having resilient connection to the cover portion and positioned along one edge of said cover portion.

These and other objects of the invention relating to the improved cover member, and all its parts and combinations will in part be obvious and in part be pointed out in the subsequent de-

tailed description and in the accompanying drawing forming a part thereof, and in the claims. The drawing illustrates a preferred embodiment and is not to be considered as limiting the invention to the embodiments shown and described. All modifications including features of construction, combinations of elements and arrangement of parts, as may be within the spirit of the invention are contemplated.

10 In the drawing wherein similar parts are designated by similar numerals:

Fig. 1 is a side elevational view of a cam hinge in closed position showing the cover member of my invention, embodying resilient end members hooked over hinge pintle projections.

Fig. 2 is an edge elevation of the hinge and cover of Fig. 1.

Fig. 3 is an end elevation of the hinge and cover of Fig. 1.

Fig. 4 is a side elevation partially in section showing a modified form of cover embodying the principles of the invention and secured to a hinge.

Fig. 5 is an end elevation of the hinge and cover of Fig. 4.

Fig. 6 is an elevational view of a further modification of the invention applied to a cam hinge and shown in 90 degree open position; and

Fig. 7 is a cross-sectional view taken at 7—7 of Fig. 6; and

Fig. 8 is a cross-sectional view taken at 7—7 of Fig. 6 showing the leaves in closed position and mounted to a door and frame.

Referring more specifically to Figs. 1 to 8 inclusive, 10 and 12 are leaves of a cam hinge that are connected through the axis of a plurality of knuckles having cooperating cam surfaces, by a pintle or connecting pin 14. It will be observed that the connecting pin projects beyond the opposite ends of the leaves to provide head portions 16 and 18. In Fig. 1, the head 16 is integral with the pin 14, while the head 18 is a nut in threaded relation with the pin 14. The heads 16 and 18 each have enlarged outer ends, an inner shoulder portion, and a neck portion 20 the purpose of which will be hereinafter understood. Manifestly the heads 16 and 18 may be omitted and the pin 14 be of sufficient length to provide projecting ends each formed with an annular groove. Moreover it will be understood that the heads 16 and 18 may be stud members secured in the end knuckles of the hinge; also that the pin 14 may be tight or loose with respect to the knuckles of either or both leaves of the hinge. Secured to the hinge is a cover or shield 22, a purpose of which is to mask to the extent

desired, the operating parts of the hinge when the hinge is assembled with respect to, for example, a door and frame, and to protect human fingers from injury as well as to give the hinge a more satisfactory appearance.

The cover 22 in Fig. 1 comprises a shaped portion 24 generally semi-circular or U-shaped in character and preferably formed of sheet metal. The portion 24 is substantially co-extensive with the knuckle portion of the assembled leaves and has a curved portion 26, the inner radius of which is preferably somewhat larger than the outer radius of the knuckles to provide operating clearance. The portion 24 is also provided with side wings 28 and 30 that extend beyond the hinge axis a suitable distance to mask as much of the knuckle portion of the hinge that is operably possible. The side wings 28 and 30 are provided with prolongations forming in effect the ears 34. These ears have openings 36 which open into the end edges of the ears 34 by slits or slots 38. Connected between the adjacent ears at each end of the cover are resilient members 40, which in Fig. 1 is shown to be a helical tension spring, the ends of which have loop portions connecting to the opposed ears 34.

It will be observed that the cover of Fig. 1 may be readily assembled to the mounted hinge, it being merely necessary to force the resilient members 40 over the knuckles 16 and 18 and so that the resilient members seat in the annular grooves 20 of the projecting head portions of the pintle. In operation of the hinge the side portions of the leaves will bear against the side edges of the cover to an extent depending upon the included angle which is to be formed between the leaves when the hinge is open a maximum amount and upon the extent to which the wings 28 and 30 of the cover extend beyond the axis of the pintle. In this action the leaves will act to displace the cover outwardly and such will occur by reason of the resiliency of the attaching members 40, these members providing sufficient give so that the cover member may respond to the required movement. Obviously when the leaves are closed the resilient members 40 will act to draw the cover toward the hinge axis and take up the movement originally traversed.

In Fig. 4 the cover member has a modified form of mounting connection. In this construction it comprises a pair of caps 42 which extend over the pintle heads 16 and 18. Preferably these caps have an internal shape to fit the pintle heads and are of molded resilient material, for instance a rubber compound or latex, making them sufficiently resilient to be forced over the irregular outline of the pintle heads. They also provide a resilient connection to the body portion 44 to permit the necessary movement of that portion when the hinge leaves are opened. Preferably the body portion 44 is integral with the caps 42 and may be, for instance, molded therewith. A similar plastic compound or one that will result in a more rigidified body portion may be used for this portion of the cover. It will be understood that the body portion may also be of sheet material, for instance, spring sheet metal, and the cap portions 42 be molded in place or otherwise secured to such portion. When the caps 42 are of substantial depth they may be slit part way, as between the points 46-46, to facilitate assembly over the pintle head. It may also be desired in certain constructions to have the caps 42 of a rigid material, for instance, metal. In such case their internal di-

5 mensions will be of sufficient extent to slip over the pintle heads, and the body portion 44 of the cover will be of the resilient material, for instance a rubber compound or latex. With either construction the side wings 28 and 30 may be of a resilient material so that these portions may be made to extend beyond the hinge axis an amount greater than ordinarily possible and give when the hinge leaves are opened outwardly, also cover and knuckles are spaced apart to provide clearance.

It will be observed that the cover of Fig. 4 is also readily assembled to the hinge, it being merely necessary to drop one cap portion over a projecting pintle head and by stretching the resilient portion of the cover force the second cap over the second projecting head of the pintle. Obviously the stretch will occur in either the body portion or the heads or at the junctions of these portions depending upon the construction of the cover. In operation of the hinge, the cover if of resilient material, will give under the bearing action of the leaves when opening and will return to normal position when the hinge is again closed. If the body portion be rigid the give will take place in the cap portions or resilient connection between the cap portions and body portion.

In Figs. 6 and 7 I have illustrated a further modification particularly adapted for use with hinges that are not provided with pintle extensions. The cover may comprise, for example, a body portion 48 and a pair of spaced extensions, tabs or lugs 50 and 52 resiliently connected to the body portion. In Fig. 8 it will be noted that the body portion has a 270 deg. circular section but it will be understood that this section may be of other shape. Also that the body portion may extend around the knuckle portion of the hinge through an arc of 180 degrees or more. The cover in the construction shown in Figs. 6 and 7 is preferably made of sheet metal, spring metal being most suited and is preferably pre-formed to the shape shown in Fig. 8. The extensions 50 and 52 are provided with internal ears or tongues 54 which are formed by a continuous group of cuts in the extensions 50 and 52. These ears have the function of holding the cover in place when it is assembled over the hinge.

In mounting the cover the extensions 50 and 52 are inserted between the knuckles on one hinge and the ears 54 of the extensions are bent outwardly against the knuckles, the ears forming in effect prolongations of the shaped body portion of the cover. In this manner the knuckle portions are surrounded through an arc exceeding 180 degrees with a distance between the ends of the arc less than the diameter of the knuckles and thereby preventing the cover from being released, also the ears 54 and the extensions 50 and 52 form spreading prongs holding the cover between the knuckles and the leaf adjacent to which they are positioned. It will be understood that the ears 54 may be struck out in making the cover member in which case the cover will be assembled by removing the pintle then separating the leaves sufficiently to insert the cover and re-assembling.

In operation the cover will remain stationary with respect to one of the leaves, for instance the leaf 56 in Fig. 6, this being either the stationary or movable hinge leaf, preferably the movable leaf (that on door). As the leaves of the hinge are separated in spreading, the edge 58 of the cover will meet the adjacent leaf 60 and will cause the cover to spring outwardly by reason of

the resilient connection with the extensions 50 and 52, the ears 54, also the resiliency of the body portion and will return to normal position when the leaves are again closed.

From the foregoing description of my invention it will be understood that I have presented a cover for hinges that is well suited for standard or cam hinges, that will operate with hinges embodying pintle projections or which lack this feature, also that my cover is simple in construction, readily assembled and foolproof. It will be understood that various changes in the constructions illustrated will readily suggest themselves to those skilled in the art but without departing from the spirit and scope of my invention. I therefore desire that my invention be construed as broadly as the following claims will permit and to embrace all equivalents.

I claim:

1. A cover for a hinge of the type having a pair of leaf members provided with knuckle sections and pintle means connecting the knuckle sections, comprising a preformed elongated substantially U-shaped body portion to cover over the knuckle sections and a pair of resilient retaining means spaced apart longitudinally of the hinge axis connected to and extending from said body portion to secure the cover to the hinge and retain said cover in place and permit displacement of said body portion with respect to the retaining means during operation of said hinge.

2. A cover for a hinge of the type having a pair of leaf members provided with knuckle sections, pintle means connecting the knuckle sections and end projections along the pintle axis adapted to receive cover retaining means, comprising an elongated relatively thin walled body portion having an open side whereby said body portion may embrace said knuckle sections and resilient retaining means bridging said open side of said body portion at its opposite ends and engageable with said end projections.

3. A cover for a hinge of the type having a pair of leaf members provided with knuckle sections, pintle means connecting the knuckle sections and end projections along the pintle axis adapted to receive cover retaining means, comprising an elongated substantially U-shaped body portion to extend over the knuckle sections and a resilient strap bridging the opposite sides of said U-shaped body portion at each end of said body portion for retaining said cover to said end projections.

4. A cover for a hinge of the type having a pair of leaf members provided with knuckle sections, pintle means connecting the knuckle sections and end projections along the pintle axis adapted to receive cover retaining means, comprising an elongated body portion to extend over the knuckle sections, said body portion being relatively thin walled and having an open side whereby said body portion may embrace the knuckle sections, a pair of projecting ears at each end of said body portion and retaining means extensible with respect to said body portion, connecting each pair of ears across said open side, said retaining means being engageable with said end projections.

5. A cover for a hinge of the type having a pair of leaf members provided with knuckle sections, pintle means connecting the knuckle sections and end projections along the pintle axis adapted to receive cover retaining means, comprising an elongated open sided body portion to extend over the knuckle sections and retaining

means extending at each end of said body portion and engageable with said end projections for attaching and retaining said cover to said hinge; at least one of said body portion or retaining means being of extensible character.

6. A cover for a hinge of the type having a pair of leaf members provided with knuckle sections, pintle means connecting the knuckle sections and end projections along the pintle axis adapted to receive cover retaining means, comprising an elongated substantially U-shaped metallic body portion to extend over said knuckle sections and resilient retaining means at each end of said body portion for attaching and holding said cover to said end projections, said retaining means connecting with the adjacent legs of said U.

7. A removable cover for a hinge of the type having a pair of leaf members provided with knuckle sections, pintle means connecting the knuckle sections and end projections along the pintle axis adapted to receive cover retaining means, comprising an elongated open sided body portion to extend over said knuckle sections, said body portion having marginal edges adjacent said opening and the opposite ends of said edges having projecting ears and extensible spring members connecting the ears at each end of said body portion and engageable with said end projections to retain said cover in position.

8. In combination a hinge comprising a pair of leaf members having knuckle sections and pintle means joining the knuckle sections and having portions along the pintle axis projecting beyond the ends of the leaves, and a cover member for said knuckle sections comprising an elongated substantially U-shaped sheet metal member having sides substantially the length of said leaves and substantially covering said knuckle sections, and resilient retaining means connecting the sides of said U at each end of said cover and assembled under tension over said projecting portions of said hinge, said retaining means being capable of extension upon outward movement of the cover member in response to motion of the hinge leaves when spreading to open position and adapted to return said cover upon closing of the hinge leaves.

9. A cover for a hinge of the type having a pair of leaf members provided with knuckle sections and pintle means connecting the knuckle sections, comprising a shaped body portion to extend over the knuckle sections, and a pair of tabs along one edge of said body portion to secure said cover to the hinge, said tabs being resiliently displaceable with respect to said body portion during operation of said hinge.

10. A cover as claimed in claim 9 wherein said tabs include resilient locking tongues engageable with adjacent knuckle sections.

11. A cover for a hinge of the type having a pair of leaf members provided with knuckle sections, pintle means connecting the knuckle sections, and knob-like end projections on the pintle axis adapted to receive cover retaining means, comprising a substantially U-shaped body portion to extend over the knuckle sections and knob-shaped rubber cap portions at the ends of said body portion and integral therewith to extend over said end projections and retain said cover in place said cap portions being thin walled and resilient and capable of permitting displacement of said body portion during operation of said hinge.

12. A device for protecting the opposite pro-

jecting ends of a hinge pindle, comprising a pair of hollow members for engaging and enclosing said pindle ends, and yieldable means for forcibly engaging said hollow members with said pindle ends.

13. A protective device, for attachment to a door hinge having a generally cylindrical exposed

portion, comprising a hollow rubber capsule having therein an opening through which said cylindrical exposed portion of the hinge may be passed to enter said capsule, said exposed portion of the hinge thereafter completely filling the hollow interior of said capsule.

CHARLES COLUCCI.
